[57] CLAIM

The ornamental design for a pair of spectacles, as
shown and described.

DESCRIPTION

FIG. 1 is a front elevational view of a pair of spectacles
embodiment my new design;

FIG. 2 is an elevational view of one side of the pair of
spectacles, the opposite side thereof being of substan-
tially the same appearance;

FIG. 3 is a top plan view of a pair of spectacles, one of
the temples of which has been broken away for conve-
nience of illustration; and

FIG. 4 is a cross-sectional view of the spectacles taken
along line 4—4 of FIG. 1 looking in the direction of the
arrows.

Fig. 4
